UNITED STATES PATENT OFFICE

2,409,470

BURNER AND FUEL FLOW CONTROL MEANS

James L. Breese, Santa Fe, N. Mex., assignor to
Oil Devices, Santa Fe, N. Mex., a limited partnership of Illinois

Application July 13, 1944, Serial No. 544,736

9 Claims. (Cl. 158—42.3)

1

My invention relates to an improvement in hydrocarbon burners and has for one purpose the provision of a burner for burning liquid hydrocarbon fuels which shall be simple, economical and efficient in operation.

Another purpose is the provision of improved means for supplying a burner through a single passage or inlet member with all of the air necessary to support the primary combustion of the fuel.

Another purpose is the provision of improved means for preventing an excess supply of fuel and for cutting off the fuel supply when an excess supply has been delivered.

Another purpose is the provision of improved means for supplying primary and secondary air for the combustion of liquid fuel hydrocarbons along a single inlet member.

Another purpose is to provide improved means for vaporizing liquid fuel in a zone of combustion in the presence and for mixture with air adequate to support partial and eventually final fuel combustion.

Another purpose is to provide an improved means for controlling the level of liquid fuel subjected to vaporization within a mixing and combustion chamber.

Other purposes will appear from time to time in the course of the specification.

I illustrate my invention more or less diagrammatically in the accompanying drawing wherein:

Fig. 1 is a vertical section through an embodiment of my device; and

Fig. 2 is a section on the line 2—2 of Fig. 1.

Like parts are indicated by like symbols throughout the specification and drawing.

Referring to the drawing, I illustrate a combustion chamber 1, herein shown as in the form of a drum, having a bottom or base portion 2 and, if desired, a bottom body 3 of any suitable material, such as fire brick. It will be understood that the burner may be applied to a wide variety of heaters, furnaces and the like, but I illustrate it in connection with a water heater 5 having a central flue passage 6. I employ a single air and fuel inlet member having an outer passage 7, herein shown as vertical, and with an open top 8, or any other suitable means for admitting air. It has a horizontal portion 9, which extends inwardly through the wall of the member 1, and is herein shown as terminating with a downward elbow 10, which may be axially aligned with the flue passage 6. I provide a fixed vaporizing cup 30 of metal or any other suitable material, which may be mounted on any suitable supports 31 or

2

may otherwise be supported or positioned within the wall 1 defining the mixing and combustion chamber. 32 is a float of any suitable material adapted to resist or be undamaged by the temperatures to which it is subjected. It may be of stainless steel or some ceramic material and is sufficiently buoyant to float on the fuel 33. 34 is any suitable operating rod upon the free end of which the float 32 is secured. It controls any suitable worm or screw 35 through any suitable nut 36 to control a valve element 37 opposed to a seating 38 in the liquid fuel inlet duct 39. It will be understood that when the level of the fuel 33 drops in response to vaporization of the fuel in the vaporizing cup 30 the constant rotation of the arm 34 moves valve 37 away from the valve seat 38 and permits an inflow of liquid fuel. Also when sufficient fuel has been supplied, the rise of the float 32 moves the valve 37 toward closing position. The duct 1 may be employed to supply all the air necessary for combustion; or additional air may be admitted through other inlets. I may provide for example the access opening 40 controlled by a movable door 41 which may have damper apertures 42.

It will be realized that, whereas I have described and illustrated a practical and operative device, nevertheless many changes may be made in the size, shape, number and disposition of parts without departing from the spirit of my invention. I therefore wish my description and drawing to be taken as in a broad sense illustrative or diagrammatic, rather than as limiting me to my precise showing.

For example, the shape and proportion of the primary and secondary air passages may be widely varied, and a single aperture or plurality of apertures may be employed, or a variety of different shapes of head. It will be understood, also, that, if I wish, I may provide some additional air supply to the combustion chamber 1, but under many circumstances it is preferable to deliver all of the air supply through the passage 1.

The use and operation of my invention are as follows:

I provide a heating device in which a liquid fuel, such as liquid hydrocarbon, may be burned. I have illustrated my device in connection with a structure suitable for a hot water heater, but it will be understood that I may apply it to space heaters, furnaces, or the like, or any other heating means.

Basically, I employ an inlet passage of substantially greater capacity than is necessary for the mere supply of a liquid fuel to be burned. In

the drawing I illustrate an air passage of substantial cross sectional area, which receives air at the open top 8 and delivers the air inwardly along the passage 9. The liquid fuel is admitted along the passage 39, past the valve members 37, 38, and flows inwardly along the passage 9. As a substantial length of the passage 9 is subjected to the heat of combustion within the member 1, the tube through which the mixture of primary air and the liquid fuel flows is highly heated. Enough air is admitted to constitute the entire primary supply of air, and the liquid hydrocarbon, in the presence of this primary air, is vaporized and forms, with the primary air, a hydroxylated mixture.

The mixture is supplied at a speed exceeding that of flame propagation, so that the mixture cannot burn back into the passage 9, with a consequent deposit of carbon. It will be understood that I may employ any means for maintaining this relatively high flow of mixture. If in any particular situation natural draft is not sufficient, I may employ a motor driven fan, or other suitable means not herein shown.

Fuel is supplied in sufficient volume to maintain a fire which will subject the member 9 to temperatures sufficient to vaporize the liquid fuel and to superheat the final mixture. When the mixture escapes from the downturned end 10 of the member 9, it receives sufficient secondary air in the space defined by the drum 1 to produce a final mixture which is burned in the combustion chamber.

I may employ any suitable inlet means for supplying this secondary air. It is advantageous to deliver the secondary air so as to maintain a zone of combustion directly adjacent the passage 10 so that the liquid fuel is properly vaporized and the primary mixture superheated.

I find it advantageous to provide means for cutting off the fuel supply in the event that an excess supply of fuel, more than can be vaporized, is delivered from the outlet 10.

Oil flows from the inlet 39 through the valve orifice into the tube 9, and flows out along the tube, which is pitched somewhat downwardly toward the mouth 10. The oil starts in as a liquid after passing the valve seat 38, and flows down the lower surface of the tube 9. Before it reaches the orifice 10 it is vaporized by the heat of combustion.

The air passing through the tube 9 is sufficient to completely hydroxylate the mixture, and a dry combustible gas flows downwardly through the orifice 10 at a velocity greater than that of flame propagation. This velocity is sufficient to prevent flame from burning back into the tube.

Any suitable secondary air supply means may be employed for supplying secondary air to the space within the drum or housing 1. It will be understood that in any event secondary air is admitted to the space within the drum 1 and that this secondary air is sufficient and effective to maintain final complete combustion of the mixture which flows from the orifice 10.

With reference to the drawing I provide means for controlling the liquid fuel valve in response to variations in the amount of liquid fuel present in the mixing chamber or zone and in the vaporizing member. Variations in the amount or level of the fuel subjected to vaporization are employed to control the liquid fuel inlet valve 37.

I claim:

1. In combination, in a liquid fuel burner, a mixing and combustion chamber element there-

for, having air inlet means, means for delivering a liquid fuel to the interior of said chamber element, a liquid fuel receiving cup, located in said interior of said chamber element and in the line of delivery of liquid fuel to the interior of said chamber element, and means for varying the flow of liquid fuel to the interior of said chamber element in response to changes in the volume of the liquid fuel in said cup.

5 2. In combination, in a liquid fuel burner, a mixing and combustion chamber element therefor, having air inlet means, means for delivering a liquid fuel to the interior of said chamber element, a liquid fuel receiving cup, located in said interior of said chamber element and in the line of delivery of liquid fuel to the interior of said chamber element, and means for varying the flow of liquid fuel to the interior of said chamber element in response to changes in the level of the liquid fuel in said cup.

10 3. In combination, in a liquid fuel burner, a mixing and combustion chamber element therefor, having air inlet means, means for delivering a liquid fuel to the interior of said chamber element, a liquid fuel receiving cup, located in said interior of said chamber element and in the line of delivery of liquid fuel to the interior of said chamber element, and means for varying the flow of liquid fuel to the interior of said chamber element in response to changes in the level of the liquid fuel in said cup, said cup being normally fixed within and in relation to said mixing and combustion chamber.

15 4. In combination, in a liquid fuel burner, a mixing and combustion chamber element therefor having air inlet means, means for delivering a liquid fuel to the interior of said chamber element, means in said chamber element for receiving said liquid fuel and for maintaining it in position for vaporization by the heat of combustion taking place within or adjacent said chamber element, and means for varying the rate of flow of liquid fuel to the interior of said chamber element in response to variations in the volume of unvaporized liquid fuel present in said chamber.

20 5. In combination, in a liquid fuel burner, a mixing and combustion chamber element therefor, having air inlet means, means for delivering a liquid fuel to the interior of said chamber element, a liquid fuel receiving cup, located in said interior of said chamber element and in the line of delivery of liquid fuel to the interior of said chamber element and means for varying the flow of liquid fuel to the interior of said chamber element, in response to changes in the volume of liquid fuel in said cup including a float member responsive to the level of liquid fuel in said cup.

25 6. In combination, in a liquid fuel burner, a mixing and combustion chamber element therefor, having air inlet means, means for delivering a liquid fuel to the interior of said chamber element, a liquid fuel receiving cup, located in said interior of said chamber element and in the line of delivery of liquid fuel to the interior of said chamber element, and means for varying the flow of liquid fuel to the interior of said chamber element in response to increases in the volume of the liquid fuel in said cup.

30 7. In combination, in a liquid fuel burner, a mixing and combustion chamber element therefor, having air inlet means, means for delivering a liquid fuel to the interior of said chamber element, a liquid fuel receiving cup, located in said interior of said chamber element, and in the line

of delivery of liquid fuel to the interior of said chamber element, and means for varying the flow of liquid fuel to the interior of said chamber element in response to increases in the level of the liquid fuel in said cup.

8. In combination, in a liquid fuel burner, a mixing and combustion chamber element therefor, having air inlet means, means for delivering a liquid fuel to the interior of said chamber element, a liquid fuel receiving cup, located in said interior of said chamber element and in the line of delivery of liquid fuel to the interior of said chamber element, and means for varying the flow of liquid fuel to the interior of said chamber element in response to increases in the level of the liquid fuel in said cup, said cup being normally

fixed within and in relation to said mixing and combustion chamber.

9. In combination, in a liquid fuel burner, a mixing and combustion chamber element therefor having air inlet means, means for delivering a liquid fuel to the interior of said chamber element, means in said chamber element for receiving said liquid fuel and for maintaining it in position for vaporization by the heat of combustion taking place within or adjacent said chamber element, and means for varying the rate of flow of liquid fuel to the interior of said chamber element in response to increases in the volume of unvaporized liquid fuel present in said chamber.

JAMES L. BREESE.
